SIGNALING MECHANISM

Filed Nov. 6, 1919

2 Sheets-Sheet 2

Fig. 2.

UNITED STATES PATENT OFFICE.

JESSE CORNELIOUS SIMS, OF MAYNARD, MASSACHUSETTS.

SIGNALING MECHANISM.

Application filed November 6, 1919. Serial No. 336,036.

To all whom it may concern:

Be it known that I, JESSE C. SIMS, a citizen of the United States, and a resident of Maynard, in the county of Middlesex and 5 State of Massachusetts, have invented a new and Improved Signaling Mechanism, of which the following is a full, clear, and exact description.

This invention relates to improvements in 10 signaling mechanism, and more particularly to an electrically operated visual and sounding signal, an object of the invention being to provide improved signals which may be seen and heard both in the light and in the 15 dark and which will be automatically operated.

A further object is to provide an improved construction of signal casing with improved rotary signals therein and im- 20 proved mechanism for operating the signals.

A further object is to provide a signaling mechanism which is adapted for use as a railroad signal, as a fire or burglar alarm, 25 or for any other use to which such a mechanism might be employed.

With these and other objects in view the invention consists in certain novel features of construction, and combinations and ar- 30 rangements of parts, as will be more fully hereinafter described and pointed out in the claims.

In the accompanying drawings—

Figure 1 is a view in elevation and partly 35 diagrammatic illustrating my invention;

Figure 2 is a fragmentary view partly in elevation and partly in section illustrating the signal casing and the mechanism therein contained, the section being taken on the 40 line 2—2 of Figure 3;

Figure 3 is a view in horizontal section through the casing;

Figure 4 is a view in section illustrating a form of contact which may be utilized in 45 connection with a burglar alarm; and

Figure 5 is a view showing a form of contact which may be used on fire alarms.

1 represents a circular signal casing which may be conveniently supported upon 50 a post 2. The casing 1 is provided in its opposite sides with segmental transparent portions 3 and 4, the transparent portions 3 being in a smaller arc than the transparent portions 4, and the transparent portions 55 3 being of a color preferably red, while the

transparent portions 4 are of plain glass or other similar material.

A platform 5 is provided in the casing 1 and a shaft 6 located centrally in the casing is supported in suitable bearing brackets 7. 60 This shaft 6 at one end is secured to the center of a bar or spider 8, the latter carrying at its ends signaling segments 9 which are located between the transparent portions 4 and are readily observed therethrough. 65 These segments 9 may be of metal or any other suitable material and are colored in various ways as may be desired. I have illustrated the segments of two colors so that as they are moved around the casing 70 and observed through the transparent portions 4, they will attract attention.

The shaft 6, above referred to, also supports a pair of radial arms 10 carrying electric lights 11 at their free ends. These electric lights move in an arc of a circle and serve to illuminate the colored transparent portions 3 of the casing. The segments 9 are designed to attract attention in the daytime, and the lamps or lights 11 illuminating the 80 transparent portions 3 will attract attention at night so that by turning the shaft 6 either in the day or in the night, the signal will be plainly seen.

An electric motor 12 is supported in the 85 casing 1 and a drive shaft 13 of the motor is provided at its respective ends with worms 14 and 15 respectively. The worm 14 transmits motion to a worm wheel 16 on shaft 6 and the worm 15 transmits motion 90 to a shaft 18 which carries a rotary disk 19, the latter being provided in its face with blocks of insulation 20 for a purpose which will hereinafter appear.

The platform 5 also supports a horn or 95 other electrically operated sounding device 21 and electro-magnets 22 are supported on the platform 5 and are adapted to attract an armature 26 which is connected to and insulated from a series of spring contacts 27, 28, 29 and 30, the latter being suitably insulated from the platform 5. The spring contacts 27, 28 and 29 are normally spaced from stationary contacts 31, 32 and 33 respectively, while the spring contact 30 is normally located in engagement with a fixed contact 34. 100

A pair of brushes 35 and 35^a insulated from the platform 5 engages contact discs 36 and 36^a, respectively, insulated from each other on the shaft 6, and these brushes and 110

discs are included in the electric circuit with the lamps 11, as will be more fully herein-after explained. The discs and brushes are designed for the purpose of maintaining an 5 electrical connection between the lamps and an exterior source of current so that the former can be illuminated during rotation of the arms 10. A pair of brushes 37 insulated from platform 5 engage the face of 10 disk 19 and are included in an electric circuit with the horn 21, as will hereinafter appear.

Electric lamps 38 are supported at the center and on the outside of both faces of 15 the casing 1 and are maintained illuminated normally.

When my improved signaling mechanism is used in connection with a railroad, I preferably utilize a rail 39 which is pressed 20 downwardly by the weight of the train to engage contacts 40 to close the circuit, and I have illustrated a source of electricity 41 which may constitute a part of the electric power system of the railroad or may be a 25 separate source as may be desired. In Figure 1, I illustrate a simple form of electric diagram which permits the carrying out of my invention, but, of course, I do not wish to be limited to any particular diagram.

30 A switch 42 may be provided to open and close the circuits manually as may be desired. A wire 43 connects one side of the battery 41 with the lamp 38 and from the lamp a wire 44 extends to the contact 34. 35 The contact 34 is connected electrically with a wire 45 extending to the other side of the battery 41 so that while the contacts 34 and 30 remain together, the circuit to the lamps 38 is closed. The wire 45 also connects to 40 one terminal of the magnets 22, the other terminal of the magnets being connected by a wire 46 with the rail 39. A wire 47 connects the contacts 40 with one side of the battery 41. Hence, when the rail 39 engages the contacts 40, the circuit through the 45 magnets will be closed as follows: from the battery 41, through the wire 45, magnets 22, wire 46, rail 39, contacts 40, wire 47, to the battery. When the magnets 22 are energized, the armature 26 and the spring contact arms 27, 28 and 29 are moved into electric contact with the contacts 31, 32 and 33 respectively.

The contacts 27, 28, and 29 are connected 55 to the wire 45 by wires 48, 49, and 50, respectively. Contact 33 is connected by a wire 51 to a lamp 61 which will be more particularly described hereinafter, the lamp 61 is connected by a wire 53^a to the brush 35, 60 and the disc 36 is connected to one of the lamps 11 by wire 52. The two lamps 11 are connected by a wire 52^a, and the second lamp 11 is connected to the disc 36^a by a wire 52^b. The brush 35^a contacting with 65 the disc 36^a is in electrical connection with

the wire 43 by a wire 53. From the foregoing connections it will be seen that when the contacts 29 and 33 engage each other, the lamps will be illuminated through the following circuit: from battery 41, through 70 wire 45, wire 50, contacts 29 and 33, wire 51, lamp 61, wire 53^a, brush 35, disc 36, wire 52, lamp 11, wire 52^b, other lamp 11, wire 52^a, disc 36^a, brush 35^a, wires 53 and 43, back to battery. 75

The contact 32, above referred to, is connected by a wire 54 with one of the brushes 37, the other brush 37 being connected by a wire 55 with the horn 21, and a wire 56 connects the other side of the horn with wire 43. When the contacts 28 and 32 are together, the circuit is from the battery, through wire 45, wire 49, contacts 28 and 32, wire 54, one brush 37, disk 19, the other brush 37, wire 55, horn 21, wire 56, wire 43 80 to the battery.

The insulated portions 20 of the disk coming into contact with the brushes 37 operate to open the circuit and hence, the horn ceases to blow for a time and then sounds 90 again so that the operation of the horn is an intermittent one and may be controlled as desired according to the length of the insulated portions on the disk.

The contact 31 is connected by a wire 57 95 with one side of motor 12 and a wire 58 connects the other side of the motor with the wire 56. When the contacts 27 and 31 are together, the circuit is as follows: from battery 41, through wire 45, wire 48, contacts 100 27 and 31, wire 57, motor 12, wire 58, and wire 43 to the battery. When the motor is thus included in circuit, it operates to give the circular motion to the segments 9 and the lamps 11 causing the signaling display 105 both in the light and in the dark, as above explained.

It will therefore be noted from the above description that normally the contacts 34 and 30 are together so that the lamps 38 will 110 remain illuminated to illuminate the outside of the casing 1. When a train presses the rail 39, the magnets 22 cause the separation of the contacts 34 and 30 to break the circuit and extinguish the lamps 38. At the same time the other contacts 27, 28 and 29 are moved so as to engage contacts 31, 32 and 33, thus closing the circuits to the lamps 11, horn 21 and motor 12. The lamps 11 and the segments 9 are moved in a circular path by means of the motor and the horn is intermittently sounded so that attention is attracted to the signaling device to indicate a warning. 115

As above stated, this signaling mechanism 125 may be utilized as a fire alarm, or a burglar alarm, or for any other purpose by the simple addition of obvious mechanism for controlling the circuits.

On top of the casing 1 I may locate a 130

transparent danger sign 60 and position the lamp 61 therein, which may be included in circuit with the lamps 11 as clearly shown in Figure 1 and as hereinbefore described.

5 The burglar alarm contact shown in Figure 4 may constitute a guard bar comprising two tubes 62 and 63 insulated from each other so that when a tool is forced through the outer tube against the inner tube, it will 10 close the electric circuit.

The fire alarm contact employs a fusible string 64 covered by a shield 65 and holding a spring contact 66 open. The fire breaks the string and the circuit is closed.

15 My improved signal may be employed with any of these circuit closing devices and may be used on a closed or open circuit system as desired.

Various slight changes may be made in the 20 general form and arrangement of parts described without departing from the invention, and hence I do not limit myself to the precise details set forth but consider myself at liberty to make such changes and alterations as fairly fall within the spirit and scope of the appended claims.

I claim:

1. A signaling mechanism comprising a 30 circular casing having inner and outer concentric transparent portions, a rotary support in the casing, signaling devices carried by said rotary support in position to be observed through said outer transparent portions, and light emitting means carried by 35 the rotary support in position to be observed through the inner transparent portions.

2. A signaling mechanism, comprising a 40 circular casing having inner and outer circular concentric transparent portions, the inner transparent portions being colored, a central rotary shaft in the casing, supports on the shaft, signaling devices carried by the supports and observable through the outer 45 series of transparent portions, and lamps

on the supports adapted to illuminate the colored transparent portions.

3. A signaling mechanism, comprising a 50 circular casing having inner and outer circular concentric transparent portions, the inner transparent portions being colored, a central rotary shaft in the casing, supports on the shaft, signaling devices carried by the supports and observable through the outer series of transparent portions, lamps 55 on the supports adapted to illuminate the colored transparent portions, and means for moving the signaling devices and the lamps in a circular path.

4. A signaling mechanism comprising a 60 circular casing having segmental transparent portions supported in an end thereof in different arcs struck about the axis of the casing, the inner of said transparent portions being colored, a rotary shaft disposed axially 65 of the casing, signaling devices carried by said shaft in position to be observed through the outer transparent portions, and incandescent signaling means carried by said shaft in position to illuminate the colored transparent portions. 70

5. A signaling mechanism comprising a circular casing having segmental transparent 75 portions supported in an end thereof in different arcs struck about the axis of the casing, the inner of said transparent portions being colored, a rotary shaft disposed axially 80 of the casing, signaling devices carried by said shaft in position to be observed through the outer transparent portions, incandescent signaling means carried by said shaft in position to illuminate the colored transparent portions, and electrical means for operating said shaft and said incandescent signaling means. 85
